UNITED STATES PATENT OFFICE.

JOSEPH ADAM BENNETT, OF REXFORD, NEW YORK.

SMOKING-PIPE-CLEANING ATTACHMENT.

Application filed January 17, 1925. Serial No. 3,129.

To all whom it may concern:

Be it known that I, JOSEPH A. BENNETT, a citizen of the United States, residing at Rexford, in the county of Saratoga and State of New York, have invented certain new and useful Improvements in a Smoking-Pipe-Cleaning Attachment, of which the following is a specification.

This invention relates to improvements in smoking pipes and has for its principal object to provide a cleaning attachment whereby the bowl of the pipe may at all times be cleaned.

One of the important objects of the present invention is to provide a cleaning attachment of the above mentioned character, wherein the same includes an ejector, the same being normally disposed in the bottom of the bowl below the usual smoke passage, the ejector being adapted for reciprocatory movement within the bowl for cleaning the latter whenever desired, the attachment being of such construction as not to interfere with the use of the smoking pipe.

A still further object of the invention is to provide a cleaning attachment for smoking pipes of the above mentioned character, wherein the attachment is carried by the pipe at all times, thus enabling the bowl to be readily and easily cleaned without the loss of any considerable length of time and labor.

A further object is to provide a cleaning attachment for smoking pipes of the above mentioned character, which will at all times be positive and efficient in its operation, the same being further simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout the same:

Figure 1 is a side elevation of a smoking pipe illustrating the finger piece for actuating the ejector, and

Figure 2 is a longitudinal sectional view through the pipe, and through the cleaning attachment embodying my invention.

In the drawing wherein for the purpose

of illustration is shown the preferred embodiment of my invention, the numeral 1 designates generally a smoking pipe of any well known construction, the same including the usual bowl 2, the stem 3, and the mouth piece 4. In the present instance, the bowl 2 is provided with an annular shoulder 5 in the interior of the lower portion thereof at a point below the opening 6 which communicates with the smoke passages 7 of the stem 3 as is more clearly illustrated in Figure 2 of the drawing. The purpose of this construction will hereinafter be more fully described.

My improved cleaning attachment comprises an ejector member 8 which is in the form of a substantially concaved disc, the same being of a diameter slightly less than the inner diameter of the bowl 2. The ejector member 8 is adapted for reciprocatory movement within the bowl and normally the same rests on the annular shoulder 5 so that the ejector member will not interfere with the usual passage of the smoke from the bowl 2 through the opening 6 into the smoke passage 7 of the stem 3. An upwardly curved tubular member 9 is arranged in the lower portion of the bowl 2, the same having one end thereof fitted in the side of the bowl at a point below the opening 6. A bracing element such as is shown at 10 extends upwardly from the bottom of the central portion of the bowl and cooperates with the upwardly extending portion of the tubular member 9 in the manner more clearly illustrated in Figure 2.

The stem 3 is provided with a longitudinally extending opening 11 in the forward portion thereof below the smoke passage 7, the forward end of the opening 11 communicating with the adjacent end of the tubular member 9. The opposite end of the longitudinally extending opening 11 communicating with the elongated cut out portion 12 provided in the bottom of the rear portion of the stem. Extending through the longitudinal opening 11 and also through the tubular member 9 is the flexible wire 13. The forward end thereof is secured to the central portion of the ejector disc 8 as illustrated at 14. The rear end of the flexible wire 13 is disposed within the cut out portion 12 and secured on the end thereof is the finger piece 15, the latter extending downwardly below the bottom of the stem 110.

3 and providing a means for actuating the flexible wire and the ejector member in the manner to be presently apparent.

Normally the parts of the cleaning attachment embodying my attachment are disposed in a manner as illustrated in Figure 2 and the smoking pipe may be used in the usual manner. When it is desired to clean the pipe by removing the tobacco and ashes from the bowl, the person using the pipe moves the finger piece 15 forwardly in the cut out portion 12 simultaneously causing a forward movement of the flexible wire 13 and as the latter passes through the upwardly curved tubular member 9, the ejector member 8 will be raised upwardly within the bowl causing the tobacco and ashes to be discharged from the top of the bowl and also the edge of the ejector disc 29 will scrape the inner wall of the bowl thus preventing the collection of the tobacco on the inner wall of the bowl. When the ejector member has reached the top of the bowl, all of the tobacco and ashes will have been removed from the bowl, thereby cleaning the latter. By moving the finger piece 15 rearwardly in the cut out portion 12, the ejector member 8 is returned to its normal position so that the same will be seated on the annular shoulder 5. The bowl may then be filled with a fresh supply of tobacco when the pipe is again to be used.

It will thus be seen from the foregoing description, that a cleaning attachment has been provided which may be incorporated with a smoking pipe in such a manner as not to interfere with the ordinary use of the pipe. Furthermore, the cleaning attachment will permit the bowl of the pipe to be readily and easily cleaned without the loss of any considerable length of time or labor.

While I have shown the preferred embodiment of my invention, it is to be understood that various changes in the size, shape and arrangement of parts may be resorted to without departing from the spirit of the invention and the scope of the appended claims.

Having thus described the invention, what I claim is:—

1. In combination with a smoking pipe

wherein the latter comprises a bowl, a stem, and a mouth piece, of a cleaning attachment for the bowl, the same comprising a disc 55 normally disposed in the bottom of the bowl below the outlet provided in the bowl for the passage of the smoke, said disc adapted for reciprocatory movement in said bowl, means for actuating the same, said means comprising a flexible wire extending into said bowl and secured to said disc, an upwardly curved tubular member arranged in the bottom of the bowl below said ejector and through which the forward portion of 65 the flexible wire is adapted to extend, and means associated with the opposite end of the flexible wire for actuating the same.

2. In combination with a smoking pipe wherein the latter comprises a bowl, a stem, 70 and a mouth piece, of a cleaning attachment for the bowl, the same comprising a disc normally disposed in the bottom of the bowl below the outlet provided in the bowl for the passage of the smoke, said disc 75 adapted for reciprocatory movement in said bowl, means for actuating the same, said means comprising a flexible wire extending into said bowl and secured to said disc, an upwardly curved tubular member 80 arranged in the bottom of the bowl below said ejector and through which the forward portion of the flexible wire is adapted to extend, means associated with the opposite end of the flexible wire for actuating the 85 same, said last mentioned means comprising a finger piece operable within a cut out portion provided therefor in the stem.

3. As a new article of manufacture, a smoking pipe bowl cleaner comprising an 90 ejector disc adapted to be located in the bottom of the bowl for sliding movement in said bowl, a guide tube associated with the center of said disc and adapted to be disposed between the disc and bottom of the 95 bowl, and a flexible disc operating wire connected at one end to the center of said disc, said wire being adapted to be slidably mounted upon a stem connected with said bowl and being provided on its other end 100 with a finger piece.

In testimony whereof I affix my signature.

JOSEPH ADAM BENNETT.
